UNITED STATES PATENT OFFICE.

HENRY D. HIBBARD, OF PLAINFIELD, NEW JERSEY, ASSIGNOR TO MANGANESE STEEL SAFE COMPANY, OF NEW YORK, N. Y., A CORPORATION OF NEW JERSEY.

SAFE OR VAULT.

SPECIFICATION forming part of Letters Patent No. 793,073, dated June 27, 1905.

Application filed October 16, 1903. Serial No. 177,249.

To all whom it may concern:

Be it known that I, HENRY D. HIBBARD, a citizen of the United States, residing in Plainfield, in the county of Union and State of New Jersey, have invented certain new and useful Improvements in Safes or Vaults, of which the following is a specification.

This invention relates to safes or vaults, the object of the invention being to provide a safe or vault comprising a body and a door, each of an integral structure of unmachineable metal—such, for instance, as manganese steel—with improved means for protecting the joint around the door.

15 A further object of the invention is the provision of a safe or vault body and door with a particular form of coöperating beads to protect the joint.

In the drawings accompanying and forming part of this specification, Figure 1 is a front view of a safe or vault body and its door with a part thereof in section. Fig. 2 is a cross-sectional view taken in line *a a* of Fig. 1, and Fig. 3 is a side view of this improved safe or vault.

The present structure, which is an improvement in part upon that shown and described in my Patent No. 662,429, dated November 27, 1900, comprises a body 2 and a door 3, which parts may be made of tough, hard, unmachineable metal—such, for instance, as manganese steel—and heat-treated in a manner similar to that set forth in said patent. In the present instance an integral bead 4 is located on the body around the doorway and is somewhat larger than that shown in said patent, it being in the present instance made up of a series of contiguous radially-located parts, projections, swells, or beads 5, shown as tapered, having spaces 6 intermediate thereof, said parts extending outwardly from a point in proximity to the jamb-surface, but sufficiently remote therefrom to leave a grinding (that is, a ground) surface 7, such ground surface being located at an angle to the jamb and preferably formed substantially square therewith, the particular angle, however, being determined by the formation of the door,

although the best results are obtained by having the surfaces substantially square with each other. The door having a step or offset 11 is likewise provided with a bead 8, formed similar to that just described, the parts 9 of which it is made up extending from a point in proximity to the edge thereof toward the center and shown as tapered, leaving a grinding (that is, a ground) surface 10, likewise shown substantially square with the periphery of the door, and which ground surface will in practice be substantially flush with and contiguous to the ground surface of the body, so that a tight spaceless metal-to-metal contact at the joint of the door will be obtained and which will extend throughout the entire length of the jamb. The body-bead 4, organized in the manner shown, comprises a duplex bead, since in addition to the bead shown and described in the patent hereinbefore referred to there are a series of radially-located beads projecting beyond such bead. The door is preferably formed with a flange 12, having bolt-openings 13 for the bolts. Located around the doorway on the interior of the safe is a bead, projection, or flange 14, similar to that shown in said patent hereinbefore referred to, the recess 15 formed thereby being connected with the jamb by a series of passages 16, which are shown terminating in the bolt-groove and in which passages are located pipes. By this improved organization there is provided around the doorway means in the form of a pair of beads effective to prevent the joint from being attacked by sledges to beat the metal at such joint, since such coöperating beads located and formed in the manner shown prevent the continuous striking of the metal at the joint with any appreciable effect.

In order to properly heat-treat manganese steel, it is well known that substantial uniformity of metal in the casting must be maintained, and this is accomplished in the present instance, notwithstanding the increased amount of metal located around the joint, by the particular manner in which the beads are formed; also, by means of the passages con-

necting the jamb with the interior of the body, both of which constitute an equivalent for lack of uniformity in the casting, since the passages insure a more equal cooling of the mass of metal during the setting of the casting, thus avoiding strains at such parts of the body, as well as the proper equalization and circulation of the heat during the heat-treatment and also the proper chilling effect and circulation of the water. Moreover, these passages or ducts also constitute a means of carrying off any fluid explosive should the same penetrate the joint around the door, since it would flow backward owing to the tapered formation of the door and the jamb until it reached the bolt-groove into which it would pass, and thence around to the bottom thereof and out through the adjacent passages into the interior of the safe, where it would be impracticable to explode it except by concussion, which would probably result in the wreckage of the entire contents of the safe, so that a successful burglarious opening of the safe would not be possible, as it is well known that a burglar is unwilling to take mutilated currency. Therefore his attacks upon a safe or vault are made with a view of avoiding this result.

One function of the bead, it is apprehended, is to permit the yielding of the metal of the door and of the body contiguous to such door under the force of an explosive, thereby to preserve a metal-to-metal joint, as heretofore explained in said patent, and this, it is apprehended, is still obtained, notwithstanding the increased size of the bead, owing to the fact that such bead is made up of a series of independent parts, so that the effect of an explosion will be localized—that is, the metal of one or two of the beads only would be disturbed, the position of the metal of the other beads remaining undisturbed, the metal of the affected bead yielding laterally or radially with the metal of the door as it is pushed inward. In other words, since, as is well known, all metals have some flowage, this being particularly true of manganese steel after it is heat-treated, in which condition it is very tough, its tendency being to yield or flow rather than break or crack, should an explosive charge be fired upon the joint of the door the metal adjacent to such joint would be forced inward, and owing to the provision of the beads as it is forced inward it can move radially or sidewise, since the metal of the beads would give or flow to permit this, and thus preserve a metal-to-metal contact as the metal of the bead flows or yields only in proportion to the disturbance or lateral bulge of the door at the point of the attack.

From the foregoing it will be seen that by providing a pair of beads formed in the manner shown all of the advantages obtained by the structure shown and described in the said 65 patents are obtained, but also the additional ad-

vantage of preventing the peining of the metal at the joint, so that the beads constitute a protection not only against attack by explosive means, but also by mechanical means.

In practice the spaces between the projections 5 and 9 could be filled in with some plastic material, if desired, prior to the painting of the structure.

Having thus described my invention, I claim—

1. A safe or vault body having a doorway and provided around said doorway with an integral bead made up of a series of distinctly independent and separated parts or beads.

2. A safe or vault body having a doorway and provided around such doorway with an integral bead made up of a series of distinctly independent and separated parts or beads radially located.

3. A safe or vault body having a doorway and provided around such doorway with an integral bead made up of a series of distinctly independent and separated parts or beads terminating in a relatively flat surface around the jamb.

4. A safe or vault body having a doorway, and provided around such doorway with an integral bead made up of a series of tapered distinctly independent and separated parts or beads.

5. A safe or vault body having a doorway and provided around such doorway with an integral bead made up of a series of tapered distinctly independent and separated parts or beads, terminating in a ground surface around the jamb.

6. A safe or vault body having a doorway and provided around such doorway with an integral duplex bead.

7. A safe or vault body having a doorway and provided around such doorway with an integral duplex bead one a continuous ring and the other made up of independent parts with spaces between such parts.

8. A safe or vault body having a doorway and provided around such doorway with an integral duplex bead one a continuous ring and the other a ring made up of separate and independent parts with spaces between such parts, such independent parts extending radially and projecting beyond said continuous bead.

9. An integral safe or vault body made up of hard, tough, unmachineable metal having a circular doorway and provided around such doorway with a pair of beads, one over the other.

10. An integral safe or vault body made up of hard, tough, unmachineable metal, having a circular doorway and provided around such doorway with a pair of beads one over the other, such duplex construction terminating adjacent to the jamb in a ground surface.

11. An integral safe or vault body made up of hard, tough, unmachineable metal, having a

- 5 circular doorway and provided around such doorway with a pair of beads one over the other, such beads terminating adjacent to the jamb in a continuous relatively flat surface substantially square with such jamb.
- 10 12. An integral safe or vault body made up of hard, tough, unmachineable metal having a doorway and provided around the same with a pair of beads one over the other, and one projecting beyond the other.
- 15 13. An integral safe or vault body of hard, tough, unmachineable metal having a circular doorway and provided around the same with a pair of beads one over the other, one made up of a series of independent parts having spaces intermediate such parts.
- 20 14. An integral safe or vault body of hard, tough, unmachineable metal having a doorway and provided around the same with a pair of beads one over the other, and one projecting beyond the other and made up of a series of independent parts having spaces intermediate such parts, such duplex bead terminating in a ground surface around the jamb.
- 25 15. An integral manganese-steel safe or vault body having a circular doorway and provided around such doorway with a ground surface and a bead formed of a series of radially-located distinct parts having spaces intermediate thereof.
- 30 35 16. An integral manganese-steel safe or vault body having a circular doorway and provided around such doorway with a ground surface and a duplex bead, one part formed of a series of separated parts having spaces intermediate thereof.
- 40 45 17. A safe or vault door provided with an integral bead made up of a series of distinctly independent and separated parts or beads.
- 50 18. A safe or vault door provided with an integral bead made up of a series of distinctly independent and separated tapered parts or beads.
- 55 19. A safe or vault door provided with an integral bead made up of a series of distinctly independent and separated parts or beads terminating in a relatively flat ground surface.
- 60 20. An integral, heat-treated, safe or vault door of manganese steel provided with an integral bead made up of distinctly separate parts having spaces intermediate such parts and terminating in a continuous ground surface around the edge of the door, located substantially square with the edge of the door.
- 65 21. A safe or vault body having a rearwardly-extending flange, said flange having passages therein located at intervals entirely around the jamb, establishing communication between such jamb and the interior of the body.
- 70 22. A safe or vault body having a rearwardly-extending integral flange with its inner edge free of juncture with the walls of the body, said flange having a plurality of passages therein.
- 75 23. An integral manganese-steel safe or

vault body having a rearwardly-extending integral flange provided with passages therein and pipes located in such passages.

24. An integral, cast, unmachineable-metal safe or vault body having a rearwardly-extending integral flange around its circular doorway prolonging the jamb thereof, such flange having transverse passages located at intervals entirely around it communicating with the interior of the body, and pipes or tubes located in such passages. 70

25. An integral safe or vault body formed of heat-treated, unmachineable metal having a rearwardly-extending integral circular flange forming part of and prolonging the jamb of such body and provided with passages establishing communication between such jamb and the interior of such body. 80

26. An integral safe or vault body, having a rearwardly-extending integral flange having passages therein and an exteriorly-located bead around its doorway. 85

27. An integral, cast, unmachineable-metal safe or vault body having a circular doorway, and a rearwardly-extending integral flange prolonging the jamb-surface thereof and provided with transverse passages located at intervals entirely around such flange, and also having a forwardly-extending, integral, exteriorly-located bead around its doorway. 90

28. An integral, cast, unmachineable-metal safe or vault body having a circular doorway, and a rearwardly-extending integral flange prolonging the jamb-surface thereof and provided with passages located in such flange communicating with the interior of the body, and also having a forwardly-extending, integral, exteriorly-located bead around its doorway with an annular surface located at the base thereof at the outer terminus of the 100 jamb-surface. 105

29. An integral, cast, unmachineable-metal safe or vault body having a circular doorway, and a rearwardly-extending integral flange prolonging the jamb-surface thereof and provided with passages located in such flange communicating with the interior of the body, and also having a forwardly-extending integral exteriorly-located bead around its doorway with an annular surface located at the base 110 of such bead at the outer terminus of the jamb-surface, and a door fitting into said jamb and having an annular surface contiguous to and substantially flush with the annular surface of the body. 115

30. An integral, cast, unmachineable-metal safe or vault body having a circular doorway, and a rearwardly-extending integral flange prolonging the jamb-surface thereof and provided with passages located in such flange at 125 intervals entirely around such flange and communicating with the interior of said body, pipes located in such passages, said body also having a forwardly-extending integral exteriorly-located bead or flange around its door- 130

way with an annular ground surface located at the base thereof at the outer terminus of such jamb, and an integral, cast, unmachineable-metal door fitting into said jamb and provided with a contiguous surface matching and substantially flush with the ground surface of said body.

31. An integral safe or vault body formed of unmachineable metal having a doorway and provided around such doorway with a rearwardly-projecting flange having passages therein and with an exteriorly-located bead, said bead being made up of a series of independent and separated parts or members.

32. An integral safe or vault body formed of unmachineable metal having a doorway and provided around such doorway with a rearwardly-projecting flange prolonging the jamb-surface and having passages therein with an exteriorly-located bead around such doorway, said bead being made up of a series of independent and separated parts or members terminating in a ground surface around the jamb.

33. A safe or vault comprising a body having a doorway and provided around such doorway with a rearwardly-projecting integral flange prolonging the jamb and having passages therein establishing communication between such jamb and the interior of the body and also provided with an exteriorly-located bead, and a door also having a bead.

34. A safe or vault comprising a body having a doorway and provided around such doorway with a rearwardly-projecting integral flange prolonging the jamb and having passages therein establishing communication between such jamb and the interior of the body and also provided with an exteriorly-located bead, and a door also having a bead, said beads terminating in a pair of ground surfaces around the joint.

35. A safe or vault comprising an integral manganese-steel body having a circular doorway and provided around such doorway with a rearwardly-projecting integral circular flange prolonging the jamb and having passages therein establishing communication between such jamb and the interior of the body and also provided with an exteriorly-located bead, and a circular door also having a bead, said beads terminating in a pair of ground surfaces around the joint substantially square with such joint.

36. A safe or vault comprising a body having a doorway and provided around such doorway with a bead made up of a series of distinctly independent parts having spaces intermediate thereof and a door having a bead around its edge.

37. A safe or vault comprising a body hav-

ing a doorway and provided around such doorway with a bead made up of a series of distinctly independent parts having spaces intermediate thereof, and a door also having a bead around its edge also made up of a series of distinctly independent parts having spaces intermediate thereof.

38. A safe or vault comprising a body having a doorway and provided around such doorway with a bead made up of a series of distinctly independent parts having spaces intermediate thereof and a door having a bead around its edge also made up of a series of distinctly independent parts having spaces intermediate thereof, the parts of the body-bead and the parts of the door-bead respectively terminating in a ground surface, said ground surfaces matching and being substantially flush with each other.

39. A safe or vault comprising a body having a doorway and provided around such doorway with a bead made up of a series of distinctly independent parts having spaces intermediate thereof, and a door having a bead around its edge also made up of a series of distinctly independent parts having spaces intermediate thereof, the parts of the body-bead and the parts of the door-bead respectively terminating in a ground surface, said ground surfaces matching and being substantially flush with each other, said body also having an interiorly-located flange prolonging the joint-surface and provided with passages therein establishing communication between the jamb and the interior of the body.

40. A heat-treated safe or vault comprising an integral body and an integral circular door, each formed of hard, tough, unmachineable metal, such for instance as manganese steel, said body having around its doorway a duplex bead made up of a series of independent members with spaces intermediate thereof, said door likewise having a bead around its edge made up of a series of distinctly independent members having spaces intermediate thereof, the members of the body-bead and the members of the door-bead terminating respectively in a ground surface, said ground surfaces matching and being substantially flush with each other, and said body having an interiorly-located flange prolonging the jamb of such body and provided with passages therein forming communication between the interior of said body and the jamb.

Signed at Nos. 9 to 15 Murray street, New York, N. Y., this 15th day of October, 1903.
